APPARATUS FOR DRYING WEBS OF MATERIAL, ESPECIALLY STENTERING MACHINES

Kenneth Somerville Laurie, Glasgow, Scotland,
assignor to John Dalglish, Glasgow, ScotlandApplication March 13, 1946, Serial No. 654,169
In Great Britain March 27, 1945

5 Claims. (Cl. 34—160)

1.

This invention relates to machines for drying webs of material such as fabric, paper or the like, especially cloth stentering machines.

In such machines it has been the practice hitherto to effect drying by blowing heated air in jets on to the upper and lower surfaces of the fabric or the like during its conveyance through the machine, and a large proportion of the air leaving the fabric is recirculated and reheated and blown again on to the fabric.

In apparatus as hitherto proposed, there has been a tendency to require an expenditure of a relatively large amount of power in circulating the heated air, owing to the frictional losses on the walls of the conduits, in passage of the air through relatively small spaces, in turbulence of the air generated by generally non-streamlined air flow, and in heat losses by conduction to the external atmosphere.

Moreover, unless the drying of a web is uniform throughout its width, it is necessary to overdry some parts in order to dry other parts sufficiently, and this may cause damage to the web or may necessitate subsequent dampening; alternatively, the web is left with some parts not sufficiently dry. These factors may have a bad effect on subsequent treatment of the web, especially in textile finishing processes.

One of the chief objects of the present invention is to provide a drying machine in which the velocity of the air is kept as low as possible in the passages, and circulation of the air is arranged so as to provide low resistance with a relatively low degree of turbulence and relatively low losses caused by sudden changes in pressure and velocity and passage through restrictions.

A further object is to minimise accumulation of fluff or dirt and consequent choking such as would occur in restricted passages.

A further object is to obtain more uniform drying across the width of the web.

Still further objects are to economise in the horse power required to circulate the air, and to enable relatively easy access to the internal parts of the machine.

I shall now describe an embodiment of the invention simply by way of example as applied to a stentering machine and with reference to the accompanying drawings whereon:

Figure 1 is a plan view of the machine with the top of the casing removed for clearness, intermediate parts of the machine being broken away.

Figures 2 and 2a show a side elevation.

Figure 3 is a cross sectional view on the line III—III of Figure 1, to a different scale.

Figure 4 is a detail diagrammatic view of the air nozzles, to an enlarged scale.

Figure 5 is a vertical section on the line V—V, Figure 3.

2.

In the machine the web 5 of cloth to be dried is carried along longitudinally in the machine between two longitudinal opposed stenter guide rails 6 (shown diagrammatically in Figure 3), said rails carrying in the usual way chains and cloth grippers. For heat insulation purposes the whole machine is enclosed in a casing comprising heat insulating panels 7 at each side and similar panels 8 at the top and end panels, all said panels being secured to an open framework 9 of angle pieces. Said panels may be made, for example, of cork-lined sheet metal, and same may be easily removable for access to parts of the machine.

The web is carried through the machine on its guide rails 6 by a mechanical drive 10 leading from driving mechanism of known construction, and the web enters the machine casing at 11 at one end and leaves at the other end at 11a, there being spaces at such ends above and below the cloth.

Within the casing is a central longitudinal air delivery chamber or conduit 12, said conduit being duplicated, having one part above the web and the other part below, as shown in Figure 3. Nozzles 34 direct drying air from inside the upper and lower delivery conduits, blowing same directly on to the cloth web.

The outer side walls of the machine casing form return air conduits 13, one on each side of the central delivery conduits, conduits 12 and 13 each being separated from each other by longitudinal partitions or walls 23, 24, also supported on angle piece framing. The parts 23a and 24a of said walls, that is, the parts in line with the guide rails 6, are provided only in the region of the air delivery fans 14 (see Figure 5) and extend over approximately the width between two air heaters 15, 15a (Fig. 1) in each case; these parts 23a, 24a thus ensure that the air cannot by-pass the heaters. The rest of the partition walls 23, 24 are continuous and leave long ports in line with the guide rails and communicating between the web space and the return conduits.

The blowers or fans shown by way of example at 14 are of axial flow type having blades 18 and a streamlined fairing 19. Each fan is driven by an electric motor 17, and the air is delivered through a diffuser 16 (one only of which is shown by way of example in Fig. 1) the said diffuser having internal dividing partitions 16a.

The diffusers 16 together with the fairings 19 provide a Venturi shaped delivery outlet, the diffuser diverging from circular formation to rectangular formation at its outlet.

It will be seen that the air delivered from the diffuser 16 to the delivery conduit 12 passes down from the upper conduit and up from the lower conduit and through nozzles 34 and on to the web 5 from top and bottom and flows over the whole

upper and lower surfaces thereof. The air then escapes transversely and the blocking effect of the guide rails 6 is overcome by the shape of the nozzles as shown in Fig. 4 (as hereinafter explained). The air then passes through into the return conduits 13 and returns towards each electric motor from each branch (left hand and right hand) as will be seen in Fig. 1, passing through two heaters 15 and 15a one in each branch, and it is re-circulated again through the fans at top and bottom.

The same circulation occurs at each pair of fans, and although two pairs only are shown in Figs. 1 and 2, there may be any number of intermediate pairs in accordance with the length of the machine.

The general circulation of the air throughout the machine is shown by the arrows, the passage of air from the cloth space between the nozzles out to the return conduits being indicated by dotted arrows in Fig. 1.

Furthermore, in a short machine there may only be one pair of fans located about the middle of the machine.

The electric motors 17 are automatically cooled by mounting the motors on spiders 22, and an annular clearance is provided at 21 whereby cooling air is drawn through apertures in the outer casing 7 as indicated by the arrows and is delivered into the main air system via the suction side of the fans.

As shown in Figure 4 the nozzles are formed by juxtaposing a series of channel plates 34 having parallel inclined side flanges, the spacing between the flanges of adjacent channels forming a parallel-sided nozzle 25 through which the air is delivered. The spaces 26 between the flanges of each channel provide passages through which the air can by-pass over and under the guide rails 6 thereby avoiding any constriction in the air passage. The nozzles may be arranged spaced four inches apart and may be of the width of $\frac{1}{4}$ inch, while the channels may be two inches deep. The channels may be supported on the framing supporting walls 23, 24 and they thus form horizontal walls of the conduits 12, with a series of nozzles 25 therein.

The axial flow propeller fans are preferably operated so as to build up a static air pressure in the delivery conduit of say $\frac{1}{2}$ or $\frac{3}{4}$ inch of water. The arrangement of the fans as described ensures that a substantially positive pressure exists all along the delivery conduits, so that uniform amounts of air are delivered through all the nozzles throughout the length of the machine.

The major part of the air in the machine is recirculated, but apart from cooling air entering at the fans, an additional amount of fresh air enters the machine at the ends 11 and 11a, and the total amount of fresh air entering may amount to only about five per cent of the air being circulated, a corresponding amount of moist air being exhausted through suitable exhaust apertures not shown.

Centrifugal fans or other blowers may of course be used instead of the axial flow fans.

By causing the return air flow to each of the fans to take place through two branches (on the left hand and right hand of the fan, see Fig. 1) and by splitting the total heating required at each fan into two heaters 15, 15a, the required speed of air delivery for a given degree of drying is halved. The resistance to air flow is proportional to the

square of the speed and this arrangement is therefore successful in reducing air resistance losses, the heaters thus operating in parallel and not in series.

The important portions of the air circuit and of the stenter, such as the air heaters, stenter rails, air nozzles and fans, are all accessible and easily dismountable and so can be easily kept clean and maintained. The air circulation circuit is left as free as possible from restrictions in order to prevent choking with fluff or dirt.

I claim:

1. A machine for air drying a web of material, including longitudinally extending stenter guide rails the width spacing between which is adjustable and between which the web is progressed through the machine; comprising in combination two inner air delivery conduits extending longitudinally one above and one below the web, two air return conduits extending longitudinally one on one outer side and the other on the other outer side of said delivery conduits, outer heat insulating conduit walls which enclose all said delivery and return conduits and define said delivery conduits, and longitudinal partition walls separating the return conduits from the delivery conduits and defining the return conduits, an electric motor and air delivery fan disposed transversely in the upper part of one return conduit and circulating air into the upper delivery conduit for delivery downwardly on to the top of the web and back over the web selvedge adjacent thereto, an electric motor and air delivery fan disposed transversely in the lower part of the other return conduit and circulating air into the lower delivery conduit for delivery upwardly onto the underside of the web and back across the web selvedge adjacent thereto, air heaters disposed longitudinally of said fans and on each side thereof in the respective return conduits, air passages through said partition walls adjacent the respective heaters allowing the air to pass from the web back through the heaters on each side of each fan for delivery to the delivery conduits, a series of air nozzles on the bottom of the upper delivery conduit and the top of the lower delivery conduit for blowing the air on to the web, said nozzles being formed as transverse slots extending over the maximum width between the stenter guide rails and including side walls defining said nozzles and extending towards the web at an inclination thereto and leaving between the side walls transverse air escape channels extending widthwise over the guide rails at the maximum width spacing thereof.

2. A machine for air drying a web of material, including longitudinally extending stenter guide rails the width spacing between which is adjustable and between which the web is progressed through the machine; comprising in combination two large inner air delivery conduits extending longitudinally one above and one below the web, two large air return conduits extending longitudinally one on one outer side and the other on the other outer side of said delivery conduits, outer heat insulating conduit walls which enclose all said delivery and return conduits and define said delivery conduits, and longitudinal partition walls separating the return conduits from the delivery conduits and defining the return conduits, an electric motor and air delivery fan disposed transversely in the upper part of one return conduit and circulating air into the upper delivery conduit for delivery downwardly on to the top of the web and back over the web selvedge adjacent

thereto, an electric motor and air delivery fan disposed transversely in the lower part of the other return conduit and circulating air into the lower delivery conduit for delivery upwardly onto the underside of the web and back across the web selvedge adjacent thereto, an axial streamlined fairing at the delivery side of each fan, a divergent diffuser surrounding the side walls of said fairing, said diffuser and fairing forming a Venturi-shaped outlet for the air from the fan air heaters disposed longitudinally of said fans and on each side thereof in the respective return conduits, air passages through said partition walls adjacent the respective heaters allowing the air to pass from the web back through the heaters on each side of each fan for delivery to the delivery conduits, a series of air nozzles on the bottom of the upper delivery conduit and the top of the lower delivery conduit for blowing the air on to the web, said nozzles being formed as transverse slots extending over the maximum width between the stenter guide rails and including side walls defining said nozzles and extending towards the web at an inclination thereto and leaving between the side walls transverse air escape channels extending widthwise over the guide rails at the maximum width spacing thereof.

3. A machine as claimed in claim 2, in which a proportion of fresh air is drawn into each fan through annular spaces around the motor and driving shaft thereby also cooling the motor.

4. A machine for air drying a web of material, including longitudinally extending stenter guide rails the width spacing between which is adjustable and between which the web is progressed through the machine; comprising in combination, two inner air delivery conduits extending longitudinally one above and one below the web, two air return conduits extending longitudinally one on one outer side and the other on the other outer side of said delivery conduits, outer heat insulating conduit walls which enclose all said delivery and return conduits and define said delivery conduits, and longitudinal partition walls separating the return conduits from the delivery conduits and defining the return conduits, an electric motor and air delivery fan disposed transversely in the upper part of one return conduit and circulating air into the upper delivery conduit for delivery downwardly on to the top of the web and back over the web selvedge adjacent thereto, an electric motor and air delivery fan disposed transversely in the lower part of the other return conduit and circulating air into the lower delivery conduit for delivery upwardly onto the underside of the web and back across the web selvedge adjacent thereto, air heaters disposed longitudinally of said fans and on each side thereof in the respective return conduits, air passages through said partition walls adjacent the respective heaters allowing the air to pass from the web back through the heaters on each side of each fan for delivery to the delivery conduits, a series of air nozzles on the bottom of the upper delivery conduit and the top of the lower delivery conduit for blowing the air on to the web, said nozzles being formed as transverse slots extending over the maximum width between the stenter guide rails and including side walls defining said nozzles and extending towards the web at an inclination thereto and leaving between the side walls transverse

air escape channels extending widthwise over the guide rails at the maximum width spacing thereof of externally removable panelling on the outer heat insulating walls to enable easy access to be had to the return conduits, apertures in said partition walls allowing access from said return conduit to the guide rails.

5. A stenter machine for treating a web of cloth material, including longitudinally extending stenter guide rails the width between which is adjustable and between which the web is progressed through the machine; and comprising in combination two inner air delivery chambers extending longitudinally one above and one below the web, two air return conduits extending longitudinally one on one outer side and the other on the opposite outer side of said delivery chambers, outer heat insulating conduit walls which enclose all said delivery chambers and return conduits and form said return conduits, longitudinal partition walls separating vertically the return conduits from the delivery chambers, said walls forming a generally rectangular structure with rectangular cross section conduits and chambers, an electric motor and air delivery fan disposed transversely in the upper part of one return conduit and circulating air into the upper delivery chamber for delivery downwardly on to the top of the web and back over the web selvedges adjacent thereto, an electric motor and air delivery fan disposed transversely in the lower part of the other return conduit and circulating air into the lower delivery chamber for delivery upwardly onto the underside of the web and back across the web selvedge adjacent thereto, said fans building up a positive pressure in said chambers, air heaters disposed longitudinally of said fans and on each side thereof in the respective return conduits, air passages through said partition walls adjacent the respective heaters and in line with the guide rails allowing the air to pass from the web back through the heaters on each side of each fan for delivery to the delivery chambers, a series of air nozzles on the bottom of the upper delivery chamber and the top of the lower delivery chamber for blowing the air on to the web, said nozzles being formed as transverse slots extending over the maximum width between the stenter guide rails and including side walls defining said nozzles and extending towards the web at an inclination thereto and leaving between the side walls transverse air escape channels extending over the guide rails.
